SAFETYPIN

John M. Abrams, Brooklyn, N. Y.

Application October 15, 1935, Serial No. 45,023

5 Claims. (Cl. 24—162)

The invention relates to locking safety-pins, and more especially to certain novel features of construction of such pins whereby the locking action may be made more secure.

5 It has for an object the provision of a pin which cannot accidentally become unfastened and which, therefore, will be found useful where a safety-pin of the ordinary type cannot be reliably utilized, and will be neat and inconspicuous in appearance and without objectionable projections.

A further object of the invention resides in the provision of simple and effective means to obviate the injuries, difficulties and annoyances due to the accidental unfastening of the pin, and 15 which may be inexpensively manufactured and expeditiously applied to the normal pin structure.

A still further object of the invention resides in the provision of an automatically actuated pin point locking element associated with the usual 20 guard provided with a safety-pin.

Another object of the invention resides in the provision of a locking element which must be manually displaced for unlocking of the pin section.

25 In carrying out the invention, the usual form of safety-pin—comprising a piece of spring wire with body portion or shank terminating at one end in a spring hinge and pin section with the opposite end turned over to receive a guard—is equipped with a coil spring element movably mounted around one leg of the customary U-shaped guard, being secured thereby at its outer end. At this end, said coil is adapted to be engaged by the pin point in closing the pin section, 30 pressing the coil backwardly and compressing the coil until the said pin point slips therewith. The free end of this coil to this end is suitably guided and held, preferably, in a longitudinal slot of the guard member.

40 An inclined or inwardly tapered depression in the wall portion of the guard member may be provided as an approach portion to the slot for convenience in assembling the coil around the one leg of the guard member, an inwardly directed, radial extension of the abutting end of the spring passing this approach portion and an inwardly directed, radial extension of the free end first riding over this approach portion and then springing into the slot.

45 The nature of the invention, however, will best be understood when described in connection with the accompanying drawing, in which:

Fig. 1 is an enlarged fragmentary longitudinal section of the novel safety-pin which is shown in elevation in Fig. 2, the section being taken on

the line 1—1 of said Fig. 2, and looking in the direction of the arrows—the pin section being indicated in a position about to be locked in the pin guard and novel locking element.

Figs. 3 and 4 are similar views illustrating the 5 pin section in locked position, Fig. 3 being a longitudinal section, on an enlarged scale and taken on the line 3—3, Fig. 4, looking in the direction of the arrows.

Fig. 5 is an enlarged elevation of the pin guard 10 with associated locking element; and Fig. 6 is an elevation of the said locking element.

Fig. 7 is a transverse section, on an enlarged scale, taken on the line 7—7, Fig. 4 of the drawing, and looking in the direction of the arrows. 15

Referring to the drawing, the novel safety-pin is formed in the usual manner of spring wire and embodies a body portion or shank 10 which terminates at one end in a spring hinge 11 and pin section 12. The opposite end of the pin is 20 bent over or arcuate, as indicated at 13, to receive frictionally a portion of a hollow pin guard 14 in which is to be located in the usual manner the pin point 15 when the safety-pin is closed.

It has been found, however, that this means of 25 holding the pin point is not reliable and that the pin point frequently becomes accidentally unfastened from its guard. Babies have been known to have opened pin and received injuries thereby. In accordance with the present in-

vention, provision is made for insuring the retention of the pin point 15 within the pin guard 14 until it is desired to release the same. To this end, the guard 14, which is of the customary 30 U-shape, is arranged to have associated there-

with around one of the legs, to wit: the leg 16 which is hollow and slit inwardly and in which the pin point 15 is adapted to locate, a movable coil spring element 17. The latter is designed to 35

be slidably mounted longitudinally of the said leg 16 and for contact with the pin point 15 when closing the safety-pin. Its inner abutting end is, for example, provided with an inwardly 40 directed radial extension 18 designed to fit into

and slide within the inwardly directed groove 19 of the guard member; and it is adapted for continual contact with the curved bottom of the leg member 16 or possibly the end 20 of the arcuate portion 13 as an abutment.

Its outer free end is likewise provided with an 50 inwardly directed radial extension 21 designed to fit into a guide slot 22 provided longitudinally in the side wall of member 16. By this expedient, the convolutions of spring 17 may be compressed, as indicated in Fig. 2, as the pin point 15 engages 55

the outermost convolution in bringing the pin section 12 downwardly for location of pin point 15 in the member 16 in the usual manner of closing a safety-pin. As soon as pin point 15 slips by the said convolution, however, the spring will expand under its inherent resiliency, riding over the located pin point until arrested at the outer end of the slot 22, and thus securely retaining the pin point against dislodgment.

10 To open the safety-pin, it is necessary merely to retract manually the spring 17 until its outermost convolution clears the pin point 15 sufficiently to free the same, whereupon, upon pressing upwardly upon the pin section 12 in the usual manner for releasing the safety-pin, the said pin point is freed from the guard 14.

For convenience in assembly and to insure retention of spring element 11 upon the guard member, it is preferred to provide the leg portion 16 thereof with an approach portion 23 juxtaposed to the slot 22 and tapering from the outer end of leg 16 upwardly toward said slot. By this expedient, the inwardly directed radial extension 21 is tensioned as it rides over the approach portion 23, in inserting the coil around member 16, until it reaches the slot 22 to spring therein and where it then remains securely to guide said coil in its reciprocations.

I claim:

- 30 1. A safety-pin formed of spring wire and embodying a body portion or shank terminating at one end in a spring hinge and pin section, the opposite end terminating in an arcuate section, a pin guard secured over the arcuate section to receive the free end of the pin section, and a coil element movably secured to the guard and adapted to be moved by the pin section in closing the pin until the same slips into the outermost convolution to be retained within the coil 40 until the latter is manually moved.
- 35 2. A safety-pin formed of spring wire and embodying a body portion or shank terminating at one end in a spring hinge and pin section, the opposite end terminating in an arcuate section, a pin guard secured over the arcuate section to receive the free end of the pin section, and a coil 45 spring element movably secured to the guard and

adapted to be contracted by the pin section in closing the pin until the same slips into the outermost convolution to be retained within the coil until the latter is manually retracted.

3. A safety-pin formed of spring wire and embodying a body portion or shank terminating at one end in a spring hinge and pin section, the opposite end terminating in an arcuate section, a U-shaped pin guard secured over the arcuate section, one leg thereof being slotted longitudinally to afford a guide and stop, and a coil element movably secured around the slotted leg with the outermost convolution having an inwardly directed, radial extension adapted to drop into the slot as the coil is located around the 15 said slotted leg.

4. A safety-pin formed of spring wire and embodying a body portion or shank terminating at one end in a spring hinge and pin section, the opposite end terminating in an arcuate section, 20 a U-shaped pin guard secured over the arcuate section, one leg thereof being slotted longitudinally to afford a guide and stop and provided with juxtaposed inwardly tapering depression, and a coil element movably secured to the slotted 25 leg with the outermost convolution having an inwardly directed, radial extension adapted to ride on the tapered depression to drop into the slot as the coil is located around the said slotted leg.

5. A safety-pin formed of spring wire and embodying a body portion or shank terminating at one end in a spring hinge and pin section, the opposite end terminating in an arcuate section, a U-shaped pin guard secured over the arcuate section, one leg thereof being slotted longitudinally to afford a guide and stop and provided with juxtaposed inwardly tapering depression, and a coil element movably secured around the slotted leg with the outermost convolution having an inwardly directed, radial extension 35 adapted to ride on the tapered depression to drop into the slot as the coil is located around the said slotted leg, the inner end of said coil being provided with an inwardly directed, radial extension 40 adapted to enter the U-shaped guard 45 to abut said guard.

JOHN M. ABRAMS.
